UNITED STATES PATENT OFFICE.

B. G. BRIGGS, OF PROVIDENCE, RHODE ISLAND, ASSIGNOR TO HIMSELF AND
T. HILTON, OF SAME PLACE.

DESIGN FOR A PAPER COLLAR.

Specification forming part of Design No. 2,843, dated July 3, 1866.

To all whom it may concern:

Be it known that I, B. G. BRIGGS, of the city and county of Providence, State of Rhode Island, have invented a new and ornamental Design for Paper Collars; and I do hereby declare that the following is a full, clear, and exact description thereof, which will enable others skilled in the art to make and use the same, reference being had to the accompanying drawing, forming part of this specification.

The drawing represents an elevation of this invention.

This invention consists in ornamenting a paper collar by a Grecian key, or, more properly speaking, by a succession of Grecian keys, whereby the collar obtains a novel and elegant appearance.

A represents a paper collar which is ornamented by a series of Grecian keys, as shown. Suitable borders, *b c*, extend near the top and bottom edges of the collar, so as to increase the effect of the Grecian border.

What I claim as new, and desire to secure by Letters Patent, is—

The design for a paper collar, as shown and described.

The above specification of my invention signed by me this 23d day of May, 1866.

B. G. BRIGGS.
